SON COMPANY, OF NEW BRITAIN, CONNECTICUT, A CORPORATION OF CONNECTICUT.

DOOR-LOCKING MEANS.

1,274,758.

Specification of Letters Patent. Patented Aug. 6, 1918.

Application filed March 26, 1918. Serial No. 224,717.

To all whom it may concern:

Be it known that I, LOGAN E. PAGE, a citizen of the United States of America, residing at New Britain, Hartford county, 5 Connecticut, have invented a new and useful Door-Locking Means, of which the following is a specification.

My invention relates to an improved locking device suitable for use in various connections, and of particular utility in connection with doors for steel lockers wherein it is desirable to have a simple yet dependable locking device which may be cheaply manufactured and assembled and yet which when 15 in operation will perform effectively and durably the intended functions. In the accompanying drawings which illustrate my invention in its preferred form,

Figure 1 is a front elevation of the inside 20 of a door such as used on box lockers showing my invention in place and in the locking position.

Fig. 2 is a similar view showing the parts in the unlocked position.

Fig. 3 is a view of the outside of part of the door shown in Fig. 1.

Fig. 4 is an edge view of the parts as they appear in Fig. 1, certain of the parts therein shown being broken away.

Fig. 5 is a detail view showing a part of the locking device in end elevation.

Fig. 6 is a section on the plane of the line 6-6, Fig. 3, showing certain parts in elevation and relatively enlarged.

Fig. 7 illustrates a detached detail.

Fig. 8 is a modification of Fig. 7 on a reduced scale.

1 represents a door. 2 represents a locking bolt or latch which in this particular instance is pivotally mounted at 3 on the inside of the door. 4 is a handle on the outside of the door by which the member 2 may be operated to lock and unlock the door in the casing, not shown, there being any suitable abutment or stop provided on such casing for engagement by said member 2. In this particular instance 5-6 are sliding bolts pivotally connected at their inner ends to the hub 2^a of the locking member 2, the pivotal points being indicated at 7-8 respectively. The outer ends of the bolts 5-6 slide through guides 9-10 respectively, which are carried by the inside of the door so that the bolts may be projected into or 50 retracted from the keepers 11-12, respec-

tively, said keepers being mounted on the door casing in the usual manner and which keepers in this instance project into the plane of movement of the door 1 so as to act as stops to limit the closing movement of the door and to cause the ends of the bolts 5-6 to align properly with the openings in the keepers 11-12 when the door is closed. Obviously, by turning the handle 4, the locking devices 2, 5 and 6 may be advanced 60 and retracted. In Fig. 1, I have shown the same advanced into the locking position, while in Fig. 2, they are retracted so that the door may be opened. Where such devices are employed with comparatively thin doors, 70 such as used for steel lockers for example, much difficulty is found in providing a comparatively simple and inexpensive yet effective and durable locking device to lock the locking devices in the door locking position, but by my improvement hereinafter described, I have been able to provide such a locking means which I have found satisfies all conditions in a most effective manner.

14 represents what I will term the latch 80 locking member. In the preferred form this member 14 is hollowed out, by being struck up from sheet metal, so as to provide a rounded locking end 15 which forms a locking abutment. One side of the member 14 85 is flattened as at 16 to provide clearance for the latch hub when the door is to be unlocked (see Fig. 2). The rear side of the hub of the latch member 2 is cut away, preferably on an arc, and as shown is provided with an up-turned lip 17 which forms a broad bearing face. The latch locking member 14 is mounted on the inner end of a key controlled rotatable plug 18, the end of said plug being squared or slabbed off, for example as shown in Fig. 5, so as to project into a central passage in the locking member 14. This passage is provided with one or more stop shoulders 19-19 (Fig. 7), whereby the end of the plug 18 may partake of a 95 limited free rotary movement before it starts to turn the locking member 14. The plug 18 may be the usual key plug such as found in a pin cylinder lock whereby the same may be operated by the usual flat key designed to actuate pin tumblers. 20 represents the cylinder portion of the pin cylinder lock which may be provided with offsets 21-21, whereby the cylinder may be securely riveted 100 to the inside of the door 1. 22 is an offset 105 110

from the cylinder 20 in which the usual pin tumblers or followers are located, which offset in this particular instance performs an additional function, namely, the function of 5 a stop to limit the turning movement of the latch locking member 14. On the inside of the latch locking member are two lugs 23-24. When the member 14 is turned in one direction the lug 23 will strike against 10 the offset 22 and check the further rotation of the member 14 in that direction, at which time the squared end of the plug 18 will bear against one of the shoulders 19 and will be caused to stop in a position to permit the 15 key to be withdrawn or inserted. When the plug 18 is turned in an opposite direction, it will turn idly for about one-quarter of a turn whereupon the squared end will pick up the shoulders 19 so that the continued 20 rotation of the plug by the key will rotate the member 14 until the other lug 24 strikes against the opposite side of the stop 22 at which time the key-plug will again be positioned so that the key may be withdrawn 25 or inserted. The member 14 may be held on the end of the plug by any suitable means, such as a washer 25 and a pin 26.

The operation of the device is as follows: When the parts stand, as shown in Fig. 1, 30 the door locking devices 2, 5, 6 are in position to lock the door closed, and the latch locking member likewise stands in a position to prevent the opening of the door locking devices, that is to say, the locking 35 device 14 is projected against, or close to, the rear side of the hub of the latch so that any attempt to turn the hub will be blocked by the engagement of one or the other end of the abutment 17 against the adjacent part 40 of the member 14. If a key is inserted in the plug of the lock and turned in a counter-clockwise direction (as viewed in Fig. 1), the plug will partake of a free movement for one-quarter of a rotation, at which time 45 the squared end of the plug will pick up the shoulders 19 so that a continued rotation of the plug for three-quarters of a turn will cause a corresponding turning movement of the member 14 leaving it finally in the position indicated in Fig. 2, wherein the key 50 may be removed. In the first position shown in Fig. 1, the lug 23 bears against one side of the stationary offset 22. When, however, the member 14 has been turned to the position shown in Fig. 2, the lug 24 will be brought to and against the opposite side of the offset 22 thus stopping the turning movement of the member 14 in the position shown in Fig. 2 in which the squared off side of 55 the member 14 lies to the rear of the hub of the latch 2 so that the latter may be freely turned by the handle 4 for the purpose of opening and closing the door 1.

From the foregoing, it is apparent that 60 the locking means is of an exceedingly sim-

ple character all the parts of which may be economically produced and easily assembled, and yet when assembled said devices afford a maximum degree of security. It will also be observed that there is comparatively 70 nothing to get out of order and to require repair or adjustment.

In some instances it may be desirable to hold the locking member 14 on the plug in such a way that there is no lost motion or capacity for independent relative movement and to that end I may provide in some instances, a locking member such as indicated at 14^a, Fig. 8, in which the central opening 75 through which the irregular end of the plug 18^a passes is shaped to said irregular end or otherwise connected therewith, so that there 80 will be no free movement.

In the preferred construction the locking member 16 is drawn up from a single piece 85 of sheet metal with the rearwardly flanged edge integral with the face so that it will furnish not only a broad bearing face for engagement with the hub abutment shoulders when the door is to be locked, but will 90 withstand effectively heavy pressure.

While I have shown and described the preferred form of my improved locking means, it should, of course, be understood that various modifications in the particular 95 design, construction, and arrangement of parts may be resorted to without departure from the spirit and scope of my invention.

What I claim is:

1. In a device of the character described, 100 a locking bolt, a rotatable hub therefor and means for rotating the same to project and retract said bolt into and out of the locking position, a locking means for co-operating with the aforesaid locking means comprising 105 a rotatable member mounted adjacent thereto and having a hub clearance wall on one side, a rotatable plug having a limited free rotary movement relatively to said member, said member when in one position engaging the aforesaid locking means to prevent the 110 operation thereof, and when in another position freeing the aforesaid locking means to permit the operation thereof.

2. In a device of the character described, 115 a locking bolt, a manually controlled movable hub for projecting and retracting said bolt, a locking means co-operating with said hub to hold the same against bolt operating movement, said means comprising a rotatable member mounted adjacent to said hub and having a hub clearance wall on one side, a rotatable cylinder lock plug carrying said member and having a limited free rotary movement relatively thereto and arranged 120 to move said member from a hub engaging position to another position to free said hub for the bolt operating movement.

3. In a device of the character described, 125 a locking bolt, a manually controlled mov-

- able hub for projecting and retracting said bolt, a locking means coöperating with said hub to hold the same against bolt operating movement, said means comprising a rotatable member mounted adjacent to said hub and having a hub clearance wall on one side, a rotatable cylinder lock plug carrying said member and having a limited free rotary movement relatively thereto and arranged to move said member from a hub engaging position to another position to free said hub for the bolt operating movement, and a stop to limit the turning movement of said rotatable member in one direction.
- 15 4. In a device of the character described, a locking bolt, a manually controlled movable hub for projecting and retracting said bolt, a locking means coöperating with said hub to hold the same against bolt operating movement, said means comprising a rotatable member mounted adjacent to said hub and having a hub clearance wall on one side, a rotatable cylinder lock plug carrying said member and having a limited free rotary movement relatively thereto and arranged to move said member from a hub engaging position to another position to free said hub for the bolt operating movement, and stops to limit the turning movement of said member in opposite directions.
- 20 5. In a device of the character described, a pivoted locking bolt, means for moving the same into the locking and non-locking position, additional locking means for engaging or freeing the first mentioned means, said additional locking means comprising a pin cylinder lock including a rotatable plug mounted adjacent to the first mentioned locking means but independent thereof, a locking device carried by said rotatable device and capable of limited free rotary movement relatively thereto, said rotatable device being hollow and covering the cylinder lock mechanism with means of connection between said parts whereby said locking device may be actuated by a key to engage the first mentioned locking device and hold it against bolt operating movement when in one position and to free said first mentioned locking device when in another position.
- 25 6. In a door locking mechanism, a bolt, a manually operable rotatable member associated therewith for moving said bolt comprising a hub having an abutment portion thereon, locking means in addition thereto comprising a rotatable cylinder lock plug mounted at one side of said hub and rotatable independently thereof, a locking device mounted on said plug having an abutment portion arranged to coöperate with the abutment on said hub when in one position to prevent the turning of the latter in the door unlocking direction, said locking member being shaped on one side to afford clearance to permit said hub to be actuated when said locking member is in another position.
- 30 7. In a lock for locker doors and the like, a manually controlled rotatable hub, a door bolt operable thereby, a key controlled locking mechanism independent of said hub and door bolt and comprising a cylinder lock carried by the door and having a rigid offset and a rotatable plug, a locking member mounted on said plug and covering the rear end of said cylinder lock, part of said plug passing through said locking member, said locking member having a passage therefor, a stop carried by said locking member and arranged for engagement by said plug whereby said locking member may be turned by said plug, a stop on said locking member arranged to engage said offset to limit the rotation of said member.
- 35 8. Locking means for locker doors and the like comprising a rotatable hub and a door bolt actuated thereby, the rear of said hub being recessed on an arc having its center remote from the center of said hub, a key controlled locking device comprising a rotatable locking member arranged in one position to project into said arc-shaped recess in said hub to prevent the operation of the latter for the purpose of unlocking the door, and arranged in another position to be withdrawn from said arc-shaped recess to permit said hub to be moved in a bolt retracting direction, a key controlled rotatable plug mounted independently of the hub and at one side thereof, said plug serving as a mounting for said locking member and having a limited rotative movement relatively thereto whereby said plug may be given a complete turn in either direction while imparting only a partial turn to said locking member.
- 40 9. In a lock for locker doors and the like, a manually controlled rotatable hub, a door bolt operable thereby, a key controlled locking mechanism independent of said hub and door bolt and comprising a cylinder lock mounted on the door at one side of said hub, a rotatable key plug, a locking member mounted thereon, a recess in said hub, part of said locking member being arranged to project into said recess to prevent the rotation of said hub when said locking member stands in that position, said hub being free to turn when said locking member is turned to another position, said locking member being hollow and housing the inner end of said cylinder lock.
- 45 10. LOGAN E. PAGE.
